HEATING MEDIUM CONTROL FOR CHARGE FORMING DEVICES
FOR INTERNAL COMBUSTION ENGINES

Filed Sept. 29, 1922

UNITED STATES PATENT OFFICE

JACOB RICHARD FRANCIS, OF FLINT, MICHIGAN

HEATING-MEDIUM CONTROL FOR CHARGE-FORMING DEVICES FOR INTERNAL-COMBUSTION ENGINES

Application filed September 29, 1932. Serial No. 591,345.

This invention relates to certain new and useful improvements in heating medium control for charge forming devices for internal combustion engines, the object being to provide novel means for controlling the application of heat so that the charge will be heated in order to produce a highly efficient explosive charge without any danger of overheating the charge, means being provided and controlled by the movement of the throttle valve of the charge forming device for preventing the heating medium from passing to the respective heating chambers when the throttle valve is in full open position.

A still further object of the invention is to provide a construction which is very simple, the parts being so arranged that they can be readily placed in position on an internal combustion engine of the ordinary construction now in use.

Other and further objects and advantages of the invention will be hereinafter set forth and the novel features thereof defined by the appended claims.

In the drawings,

Figure 1 is a side elevation of a portion of an internal combustion engine showing the application of my improved construction of heating medium control; and

Figure 2 is a vertical section through the same.

In the drawing 1 indicates an internal combustion engine provided with an intake manifold 2 and an exhaust pipe 3 which is provided with a valve casing 4 in which is mounted a valve 5 for completely closing the exhaust passage leading to the muffler for the purpose hereinafter fully described.

The exhaust pipe 3 is provided with an outlet 6 to which is connected by a bolt 7 a casting 8 which is provided with a passage 9 communicating with the passage 6, said passage 9 being in communication with a heating chamber 10 surrounding the main portion of the intake manifold 2.

The manifold 2 is secured to a vertical extension 11 of the casting 8 by bolts 12 and the chamber 10 surrounding the central portion of the manifold is provided with an outlet 13 which registers with an inlet 14 of a

heating chamber 15 surrounding the mixing chamber of a charge forming device 16 herein shown in the form of the well known type of carburetors now on the market known as the Marvel carburetor.

The carburetor 16 is connected to the lower portion of the intake manifold in the usual manner and extending through the main passage of the manifold is a passage 17 in communication with the heat chamber 10 and forming a hot spot in the passage of the explosive charge passing therethrough so as to heat the heavier particles of fuel to vaporize the same in their passage to the internal combustion engine and at the same time, the passage is heated by the heat jacket surrounding the same and as the charge forming device is provided with a heat chamber, the heavier particles of fuel are thoroughly vaporized before they reach the internal combustion engine.

The carburetor is provided with a throttle valve, not shown, mounted on a stem 18 which carries a pair of arms 19 and 20. The heat chamber 15 of the charge forming device 16 is provided with an outlet nipple 21 which is connected to an inlet nipple 22 of the valve casing 4 by a pipe 23 to the muffler side of the throttle valve 5 located therein so that when the valve 5 is in closed position, the exhaust gases from the internal combustion engine are conveyed through the passage 9 of the casting 8 into the heat chamber 10 of the intake manifold, then into the heat chamber 15 of the charge forming device and out the outlet thereof through the passage 23 back into the valve casing 4 and thence to the muffler in the usual manner.

In order to prevent the explosive charge from being overheated when running at high speed and to control the application of the exhaust gases to the heat jackets to a nicety, I provide the valve 5 with a stem 24 on which is secured an arm 25 which has a connecting rod 26 adjustably secured in the end thereof as shown at 27, the other end of the rod being provided with a hook 28 adapted to be placed in one of the openings formed in the arm 20 of the throttle valve stem 18 of the charge forming device. The arm 20 is provided with

100

an enlargement at its ends provided with two openings adapted to receive the hooked end of the rod 26, one of the openings being adapted to receive a rod for adjusting the relative position of the throttle valve to the valve 5 for summer use and the other being adapted to receive the hooked end of a rod for adjusting the position of the valves in respect to one another for winter use and it will be seen by this construction that as the throttle valve of the charge forming device is opened and closed, the valve 5 of the valve casing 4 of the exhaust line is opened and closed so as to throttle the exhaust gases to control the application of the gases to the charge formed in the carburetor.

In order to form positive means for preventing any of the exhaust gases from circulating through the heating chambers of the intake manifold and charge forming device when the throttle valve is in full open position, I provide the outlet nipple 21 with a valve 29 to the stem of which is connected an arm 30 which is connected to the arm 19 by connecting link 31 so that when the throttle valve of the charge forming device is in full open position, the valve 29 will be closed so as to completely cut off the circulation of the exhaust gases to the heat chamber.

This construction provides means for preventing a certain amount of the exhaust gases from circulating through the heat chamber by the back pressure caused by the valve 5 in the exhaust line pipe and positively prevents the application of heat when the throttle valve of the charge forming device is in full open position.

What I claim is:—

1. The combination with an internal combustion engine having an exhaust pipe, intake manifold and a charge forming device connected thereto, of a heating jacket surrounding the central portion of said intake manifold in communication with said exhaust pipe, a heating jacket surrounding the mixing chamber of said charge forming device in communication with the first mentioned heating jacket, a throttle valve for said charge forming device, a throttle valve for the exhaust pipe, a pipe connecting the heating jacket of said charge forming device to the exhaust pipe to the muffler side of the throttle valve thereof, a connection between the throttle valve of the charge forming device and the throttle valve of the exhaust pipe, a valve disposed within the outlet of the heating jacket of said charge forming device and a connection between said valve and the throttle valve of said charge forming device.

2. The combination with an internal combustion engine having an exhaust pipe, intake manifold and a charge forming device connected thereto, a valve casing disposed within said exhaust pipe having a throttle valve and an inlet to the muffler side of said valve,

a heating jacket surrounding the central portion of said intake manifold in communication with said exhaust pipe to the engine side of the throttle valve thereof, a passage extending transversely through the intake manifold and in communication with the heating jacket thereof, a heating jacket surrounding the upper portion of said charge forming device in communication with the heating jacket of the intake manifold, said last mentioned heating jacket being provided with an outlet, a pipe connecting said outlet to the inlet of said valve casing, a throttle valve for said charge forming device, a valve in the outlet of the heating jacket of said charge forming device and rods connecting respectively said valves for causing the valve in the exhaust pipe to be moved into full open position and the valve in the outlet of said charge forming device into closed position upon the full open position of the throttle valve of said charge forming device.

3. The combination with an internal combustion engine having an exhaust pipe, intake manifold and charge forming device connected thereto, a casing secured to said exhaust pipe having a passage, said intake manifold having a heating jacket in communication with said passage and provided with a transverse passage extending through the passage of said intake manifold and in communication with the heat jacket thereof, a charge forming device connected to the intake manifold having a heating jacket surrounding the upper portion thereof in communication with the heating chamber of said intake manifold, the heating chamber of the charge forming device being provided with an outlet passage, a valve in said outlet passage, a throttle valve for said charge forming device and a connection between said throttle valve and the valve of said outlet passage.

4. The combination with an internal combustion engine provided with an exhaust pipe, of an intake manifold connected to said engine having a heating chamber surrounding the central portion thereof and provided with a passage extending through the induction passage of said intake manifold, said exhaust pipe being provided with an opening, a casting secured to said exhaust pipe having a passage in communication with said opening and the heating chamber of said intake manifold, a charge forming device connected to said intake manifold having a heating jacket provided with an outlet passage, a valve in said outlet passage, means for throttling the exhaust pipe, a throttle valve for said charge forming device having a connection with said throttling means and a connection between the throttle valve of said charge forming device and the valve in the outlet of the heat chamber thereof.

5. The combination with an internal com-

bustion engine having an exhaust pipe connected thereto, carrying a valve casing provided with a throttle valve and an inlet to the muffler side of the valve thereof, of a manifold connected to said engine having a heating jacket in communication with the exhaust pipe thereof, a charge forming device connected to said manifold having a heating chamber in communication with the heating chamber of said manifold and provided with an outlet, a pipe connecting said outlet to the inlet of said valve casing, a valve in said outlet, a throttle valve for said charge forming device, a connection between said valve and said throttle valve and an adjustable connection between said throttle valve and the valve of said exhaust pipe.

In testimony whereof I hereunto affix my signature.

20 JACOB RICHARD FRANCIS.
